CLAIM

The ornamental design for an automotive grille, as shown and described.

DESCRIPTION

FIG. 1 is a front view of an automotive grille showing an embodiment of my new design;

FIG. 2 is a rear view thereof;

FIG. 3 is a top view thereof;

FIG. 4 is a bottom view thereof;

FIG. 5 is a left-side view thereof;

FIG. 6 is a right-side view thereof;

FIG. 7 is a perspective view thereof;

FIG. 8 is a front view of an automotive grille showing a second embodiment of my new design;

FIG. 9 is a rear view of FIG. 8;

FIG. 10 is a top view of FIG. 8;

FIG. 11 is a bottom view of FIG. 8;

FIG. 12 is a left-side view of FIG. 8;

FIG. 13 is a right-side view of FIG. 8; and,

FIG. 14 is a perspective view of FIG. 8.

The portions shown in phantom provide context only but do not limit the claim and should not be considered part of the claimed design.
